YARN BALL HOLDER

Filed May 20, 1939

FIG. 1.

FIG. 2.

INVENTOR:
Sigrid Miller
BY David E. Carlson
ATTORNEY.

UNITED STATES PATENT OFFICE

2,194,609

YARN BALL HOLDER

Sigrid Miller, Porter, Minn.

Application May 20, 1939, Serial No. 274,839

1 Claim. (Cl. 24—3)

My invention relates to improvements in a device best designated as a yarn ball holder and comprising a simple and highly efficient device for suspending a ball of yarn or other strand material in convenient position for unwinding the strand as used, for example by a person doing crochet work, tatting, darning or other work requiring such strand in a slowly progressive unwinding action.

10 In the use of this device a ball of yarn or other strand material may be suspended from the arm of a person doing work of the kind stated, or the ball may be suspended from any other convenient place near the work requiring gradual use of the thread. A feature of this device is its extreme simplicity and application, allowing strand to be unwound freely and unhampered.

In the accompanying drawing:

20 Fig. 1 is an elevation of a preferred embodiment of my device in position connected to and suspending a ball of yarn, and Fig. 2 is a modification of Fig. 1 omitting the ball of yarn.

Referring to the drawing by reference letters 25 like characters designate corresponding parts in both views, the suspending means of my device comprises preferably a length of light chain A preferably about two and one-half inches in length.

30 From the lower link of said chain extends a wire hook member B of approximately the shape of a common fish-hook the eye end of which is engaged permanently in said link and the hook end is bent out and upwardly in inclined plane 35 as a prong designated B2.

C designates an arm band which may comprise as shown a single loop of wire the connecting ends of which may comprise a small eye C2 engaging a larger eye C3 the latter being elongated to form a shank C4 which may be sprung out to insert or remove the uppermost link of the chain.

D designates a closing type of spring metal pin resembling an elongated safety pin. In Fig. 45 1 this pin is on the ring C and may be used to fasten onto any convenient article such as the cloth in a sleeve, a curtain or other convenient object by which the entire device may be suspended.

50 As a variation, shown in Fig. 2, the ring C is removed, pin D being connected directly to the top link and said pin engaging a horizontally

disposed object designated by the outline E (dotted) which may represent a belt, or the rim of a work basket placed at the edge of a table (not shown).

5 In Fig. 1 designates a common type of crochet thread ball usually wound in a nearly globular form about an open core S2 the ball being shown in suspension and engaged by the prong B2 at or near the core S2. The free end of the thread, designated S3, is shown extending from the ball. 10

The thread may be unwound as used, freely and unhampered, such thread balls being ordinarily machine wound on a bias around the core. The chain construction disclosed allows of course only a limited circular movement of the ball in 15 horizontal plane but sufficient to permit easy unwinding of the thread and simultaneously prevents the thread from contacting and in any way becoming entangled on the suspension chain.

20 In the use of the device with ring C (per Fig. 1) the ring is an arm band slipped for example on the right arm of a person, toward the elbow, the yarn or crochet thread ball being thus suspended the thread S3 unwinds from the ball in a direction away from the chain as shown. 25 Obviously the ring can also be slipped over and upon the front end of an arm rest of a chair and the ball S is thus suspended absolutely free from contact with a garment or other object.

25 The use of my device has been fully disclosed 30 simultaneously with the foregoing description of its preferred and modified construction.

I claim:

35 In a holder of the class described, the combination of an upper suspending member, an intermediate elongated, flexible member and a lower hook member, all connected, the said intermediate member comprising a length of chain removably connected to said upper member, said lowermost member comprising a wire hook 40 formed with an eye engaging the lowermost link of said chain and the hook depending therefrom, the lower part of said hook comprising an upwardly and outwardly directed prong adapted to be engaged in the side of a ball of strand material, said upper or suspending member comprising a loop of wire or the like formed with interengaged eye-loops at its closed end, one of said eye-loops elongated and adapted to be opened for insertion of or removal of the uppermost 45 link of the said chain.

SIGRID MILLER.
